UNITED STATES PATENT OFFICE.

GORDON E. ROEDDING AND EDWARD B. ROEDDING, OF DETROIT, MICHIGAN.

PUSH-BUTTON.

1,135,926.

Specification of Letters Patent. Patented Apr. 13, 1915.

Application filed February 6, 1914. Serial No. 816,916.

To all whom it may concern:

Be it known that we, GORDON E. ROEDDING and EDWARD B. ROEDDING, citizens of the United States of America, residing at Detroit, in the county of Wayne and State of Michigan, have invented certain new and useful Improvements in Push-Buttons, of which the following is a specification, reference being had therein to the accompanying drawings.

This invention relates to push buttons, and the primary object of our invention is to provide a push button or compact switch wherein positive and reliable means are employed, as hereinafter set forth, for controlling or independently completing electrical circuits used in connection with a unitary device or separate and distinct appliances.

Another object of this invention is to provide a push button with a plurality of compactly arranged contacts that may be easily and quickly actuated to complete a desired electrical circuit, and it is in this connection, that the button has been especially designed for installation upon the steering post of an automobile, whereby the chauffeur or operator of the machine may readily control various electrical circuits used throughout the machine or in connection with a single accessory thereon.

A further object of this invention is to provide a push button of the above type embodying a plurality of strong and durable parts that are easy to assemble and maintain in operable condition, and highly efficient as an electrical switch.

We attain the above and other objects by a mechanical construction that will be hereinafter specifically described and then claimed, and reference will now be had to the drawing, wherein,

Figure 1 is a plan of the push button with the cover or cap thereof removed; Fig. 2 is a similar view of the push button with the cover or cap in place; Fig. 3 is a cross sectional view of the push button, and Fig. 4 is a view similar to Fig. 1, illustrating the electrical connections of the device.

In the drawings 1 denotes a base plate that is preferably circular in plan view and secured to said base plate by screws 2 or other fastening means, is a circular plate or disk 3 made of insulating material, as fiber or rubber. The top of the plate 3 has a central circular recess 4 having for its walls

an annular wall or holder 5 that is preferably made integral with the circular plate 3.

Mounted in the holder 5 are diametrically opposed binding posts 6, 7, 8 and 9, preferably in the form of screws, and adjacent to each binding post is a slit or slot 10 approximately half the depth of the holder. The slits or slots 10 accommodate the outer ends of tangentially disposed resilient contact arms 11, 12, 13, and 14, that extend inwardly to a point in proximity to the vertical axis of the device. The inner ends of the arms 11 to 14 inclusive are contiguous to the inner ends of the binding posts or screws 6 to 9 inclusive and constitute contact members adapted to complete electrical circuits when brought into contact with the inner ends of the binding posts. The outer ends of the contact arms are bent against the outer side of the contact holder 5 and secured thereto by screws 15 or other fastening means, serving as binding posts, as will hereinafter appear.

The contact holder 5, adjacent to the binding post 9, has the wall thereof cut away, as at 16 and secured to said holder in proximity to the plate 3 and within the cut away portion of the holder is a flat contact member 17, which extends inwardly to a point centrally of the recess 4 and is provided with a vertical pin 18, as best shown in Fig. 3. The contact member 17 is held in position by a binding post or screw 19 and adjacent to the binding post 19 is another binding post or screw 20 employed for holding a spiral resilient contact member 21 above and out of contact with the pin 18. The spiral contact member 21 is of the ordinary and well known type used in connection with a push button and is adapted to be depressed to engage the pin 18 and establish an electrical circuit independent of the contact arms 12 to 14 and the binding post associated therewith.

The circular plate 3 is of less diameter than the base plate 1 and thereby provides an annular seat for a cover or cap 22 that rests upon the contact holder 5 and is adjustably secured in position to inclose the various contacts of the push button. Centrally of the cover 22 there are intersecting slots 23 disposed at right angles to one another and providing branches corresponding in number to the contact arms of the push button.

Slidably mounted upon the cover 22, over the slots 23, is a socket member or slide

button 24 having a concentric sleeve 25 extending through the slots 23 into the casing formed by the base plate 1 and the cover 22. The sleeve 25 is exteriorly screw threaded 5 and screwed thereon is a retaining plate 26 and an insulating member 27 made of fiber or rubber. The member 27 is circular in plan view and the sides or periphery thereof is engaged by the contact arms 11 to 14 inclusive, as best shown in Fig. 3.

Movable longitudinally of the sleeve 25 is the push rod or shank 28 of a push button 29 located within the socket of the member or slide button 24. Encircling the rod or shank 28, between the button 29 and the bottom of the slide button 24 is a coiled compression spring 30 that retains the push button 29 normally elevated or in a projected position. The inner end of the push 15 rod or shank 28 is provided with a contact head 31 adapted to engage the central portion or inner convolution of the spiral contact member 21 and shift said member into engagement with the pin 18 of the member 20 26 17 to complete an electrical circuit, in a manner similar to an ordinary push button.

The space within the casing, between the contact holder 5 and the walls of the cover 22 provides sufficient clearance for leading- 30 wires which enter the casing through a sleeve 32 carried by the base plate 1 and an opening 33 formed in the circular plate 3.

As illustrated in Fig. 4, a leading-in wire 34 is connected to the binding post 9 and by 35 branches, to the binding post 19, 8, 7 and 6. A leading-out wire 35 is connected to the binding post of the contact arm 14, and in a like manner wires 36, 38 and 39 are connected to the binding posts of the arms 13, 40 45 12 and 11, respectively. Another wire 37 is connected to the binding post 20 of the member 21. These leading-out wires may be assembled in a cable extending through the sleeve 32 and the opening 33, and then the proper connections established.

As an example of means for attaching the push button to its support, there is illustrated in Fig. 3, a two-part clamp employed for connecting the push button to a steering post of a steering wheel therefor. One part 40 of the clamp is preferably formed integral with the base plate 1 and the detachable part 41 of said clamp is connected to the part 40 by set screws 42 or other 50 55 fastening means.

The slide button 24 constitutes means upon the casing of a push button for shifting one of the contact arms 11 to 14 inclusive into engagement with one of the binding posts 6 to 9 inclusive, as the slide button 24 is guided by the slots 23 in the proper radial directions to deflect the arms into contact with their posts. The resiliency of the several contact arms operates to yieldingly hold the button in an axial position

relative to the casing and to return it to that position when moved therefrom as well as to break the circuits when the button is released.

As an instance of the operation of the button, we will assume that the button 24 is shifted to the right. The member 27 then contacts with the resilient arm 13 and said arm is shifted into engagement with the binding post 7 completing the following 75 circuit:—from the leading end wire 34 through the binding post 7, arm 13 and screw 15 to the leading out wire 36. With these wires in circuit with a suitable source of electrical energy the operation of various 80 devices or appliances can be easily controlled.

From the foregoing it will be observed that the capacity of the device for closing independent open circuits simply depends 85 upon the size and number of sets of contacts arranged within the casing, and other means than the intersecting slots 23 may be employed to direct the button which may be movable upon the casing as shown, or otherwise arranged, but when these slots are used they are preferably covered, as shown, by the plate 26 to prevent dirt, water, etc., from getting into the casing and interfering with the operation of the electrical contacts. 90 95

It is thought that the operation and utility of the push button will be apparent without further description, and while in the drawing there is illustrated a preferred 100 embodiment of the invention, it is to be understood that the structural elements are susceptible to such variations and modifications as fall within the scope of the appended claims. 105

What we claim is:—

1. A push button comprising a casing, a plurality of sets of electrical contacts within said casing, and means shiftable radially of said casing for independently establishing 110 electrical circuits through said contacts.

2. A push button comprising a casing, a plurality of independent sets of electrical contacts within said casing, a slide button adapted to be shifted radially of said casing to establish independent electrical circuits through said contacts, and means carried by said slide button and operable independent thereof for establishing a circuit 115 independent of the first mentioned circuits. 120

3. A push button comprising a casing, independent sets of contacts arranged within said casing around the center thereof, and a slide member shiftable radially of said casing to establish independent circuits 125 through said contacts.

4. In a push button, the combination with a casing having axial means for establishing an electrical circuit, of a plurality of sets of contacts arranged within said casing, and 130

- means shiftable radially upon said casing for establishing independent circuits through said contacts independent of said axial means.
5. In a push button, the combination with a casing, and push button actuated contacts within said casing for completing an electrical circuit, of independent sets of contacts arranged within said casing, and means normally held in position to actuate said push button contacts and shiftable radially in said casing to actuate either set of contacts within said casing to complete an electrical circuit.
10. In a push button, the combination with a casing, a contact therein, a resilient spiral contact member adapted to engage said contact, of a shiftable button for moving said resilient spiral member, and independent sets of contacts arranged within said casing, and adapted to be actuated by the shifting of said button to close the circuits in which said contacts are connected.
15. A push button comprising a casing, an annular insulated contact holder arranged therein, independent sets of contacts carried by said holder, and a slide button shiftable in radial directions upon said casing to establish independent circuits in connection with said contacts.
20. A push button comprising a casing, an insulated contact holder arranged therein, independent sets of contacts carried by said holder, a slide button shiftable in radial directions upon said casing to establish independent circuits in connection with said contacts, a push member carried by said slide button, and means within said casing engaged by said push member adapted to complete an electrical circuit in connection with circuits of the first mentioned contacts.
25. A push button comprising a casing, a contact holder arranged therein, independent sets of contacts carried by said holder, a slide button shiftable upon said casing, and means supported by said slide button within
- said casing and normally engaging certain of said contacts whereby a movement of said slide button establishes a circuit through either set of contacts, and means within said casing and operable in conjunction with said slide button for establishing a circuit independent of the first mentioned circuits.
30. A push button comprising a casing, a shiftable insulated member in the casing, resilient contact arms arranged around said shiftable member and normally in contact therewith to hold the same centrally within the casing, contacts to be engaged by the arms when flexed, and means for shifting the said member to flex said arms.
35. A device of the type described comprising a casing, a contact holder arranged therein, binding posts carried by said holder, resilient contact arms carried by said holder and adapted to engage said binding posts, a slide button movable upon said casing, means carried by said button and normally engaging said arms whereby one of said arms can be moved independently of the other arm, and a push member carried by said slide button and adapted to establish an electrical circuit independent of the circuits established by said binding posts and said resilient arms.
40. In a push button, a casing, a plurality of resilient contact arms arranged therein and adapted to independently complete electrical circuits, means shiftable upon said casing for independently moving said contact arms, and means capable of actuation in connection with the first mentioned means for establishing an electrical circuit independent of circuits through said resilient contact arms.
45. In testimony whereof we affix our signatures in presence of two witnesses.
